Henry Cordes Inventor

By A.W. Freeman

Attorney

UNITED STATES PATENT OFFICE.

HENRY CORDES, OF SIOUX FALLS, SOUTH DAKOTA.

LADDER.

Application filed March 13, 1924. Serial No. 699,005.

To all whom it may concern:

Be it known that I, HENRY CORDES, a citizen of Prussia, Germany, residing at Sioux Falls, in the county of Minnehaha 5 and State of South Dakota, have invented certain new and useful Improvements in Ladders, of which the following is a specification.

This invention relates to certain new and 10 useful improvements in ladders and the primary object thereof is to provide a ladder which can be moved by the user from place to place without descending to the surface on which the ladder is supported.

15 A further object of the invention is to provide a ladder having similar sections and novel means for connecting the sections so as to allow the latter to each have universal movement and to latch same in any adjusted 20 position thereof, as well as to permit the sections to be firmly supported on uneven surfaces.

25 A further object of the invention is to provide novel means for suspending a bucket or the like from the top of the ladder so as to be accessible from either side of the ladder.

30 The invention has still further and other objects which will be later set forth and manifested in the course of the following description.

In the drawings:—

35 Figure 1, is a perspective view of the invention; Figure 2, is an enlarged detail view, partly in section of one side of the connection between the sections;

40 Figure 3, is a view similar to Figure 2 but taken at right angles thereto;

45 Figure 4, is a section on line 4—4 of Figure 2, and

Figure 5, is a section on line 5—5 of Figure 2.

50 In proceeding in accordance with the present invention, each section of the ladder is constructed alike and is of generally inverted V-shape, having standards or side rails 1 provided with the usual rungs 2.

55 A casting is connected to the top of each section and has a stem or shank 3, the lower end of which is formed with a flared socket 4 which latter is of rectangular cross-section. The upper end of the shank 3 is formed with an integral ball head 5, the junctural points of the head and shank being formed with an undulating portion 6, which is somewhat

of corrugated form, presenting alternating depressions and swells.

As depicted in Figures 2 and 5 of the drawings, the upper ends of the stiles or 60 rails 1 are mitered at 7 so as to abut and closely fit within the sockets 4, being held fixed therein by bolts 8.

The balls 5 are received within the sockets 10 of a twin-socket housing 9, the sockets 10 of which are formed with swells and depressions 11, corresponding to the swells and depressions 6 of the stems 3, the swells and depressions of the stems being received in the depressions and swells respectively of the 70 sockets, whereby to latch the parts in any position to which same may be adjusted.

The connecting part or web 12 of the housing is formed with a depending apertured ear 13 to receive a hook 14, dotted 75 lines Figure 1, by means of which a bucket 15 may be suspended between the two ladder sections and rendered accessible from either section. Latches 15^a—15^b may be employed to removably latch the sections. 80

From the foregoing it will be apparent that the ladder sections are permitted to have universal movement in the respective sockets of the twin-socket connection and are latched in position, and that due to such 85 universal movement of each section, the ladder will be firmly supported on uneven surfaces.

In operation, the user places one foot on the desired rung of one section and the 90 other foot on the corresponding rung of the other section so that his body is in alignment with the space between the sections. If he desires to move the ladder without descending to the floor, he imposes his weight 95 on the section facing the direction in which he wishes to move, and then with his foot draws the other section toward the first section, and by then transferring his weight to the second section, with his foot moves 100 the first section away from the second section. In this manner the ladder may be moved in various directions.

What is claimed is:—

1. In a ladder, a pair of similar sections, 105 each having stiles tapering upwardly and connected by a series of rungs, the upper ends of the stiles being mitered and abutting, members having shanks formed with depending flared sockets to conformably receive the said mitered ends of the stiles 110 therein balls on the upper ends of the

shanks, bolts extending through the sockets and said stile ends to fixedly connect the parts, said shanks being formed with alternating swells and depressions adjacent the 5 bases of the balls, and a twin-socket connection for the sections, the balls being received in the respective last named sockets, the circumferential edges of the last named 10 sockets being formed with swells and depressions for engagement with the respective depressions and swells of the ball shanks, said connection being formed with a depending apertured ear disposed in the 15 space between the twin sockets for support of a bucket or the like.

2. In a ladder, a pair of similar sections, each having stiles tapering upwardly and connected by a series of rungs, the upper 20 ends of the stiles being mitered and abutting, members having shanks formed with depending flared sockets to conformably receive the said mitered ends of the stiles therein balls on the upper ends of the shanks, bolts extending through the sockets 25 and said stile ends to fixedly connect the parts, said stem being formed with alternating swells and depressions adjacent the bases of the balls, and a twin-socket connection for the sections, the balls being received in the respective last named sockets, 30

the circumferential edges of the last named sockets being formed with swells and depressions for engagement with the respective depressions and swells of the ball shanks.

35

3. In a ladder, a pair of substantially similar sections each of substantially inverted V-shape, a ball on the apex of each section, and a twin socket connection for the balls to allow each of the latter to have 40 universal movement.

4.

In a ladder, a pair of substantially similar sections each of substantially inverted V-shape, a ball on the apex of each section, a twin-socket connection for the 45 balls to allow each of the latter to have universal movement, and means to latch the sections in any adjusted position thereof.

5.

In a ladder, a pair of substantially similar sections, each of substantially inverted V-shape, a ball on the apex of each section, a twin-socket connection for the 50 balls to allow each thereof to have universal movement, the balls and sockets having swells and depressions for inter-engagement to latch the sections in any position in which same may be moved.

55

In testimony whereof I affix my signature.

HENRY CORDES.
